UNITED STATES PATENT OFFICE.

ELMER MARCUS HICKS, OF SCHENECTADY, NEW YORK.

BRAKE AND LOCK FOR SLIDING SASHES.

1,283,514.

Specification of Letters Patent.

Patented Nov. 5, 1918.

Application filed May 16, 1918. Serial No. 235,024.

To all whom it may concern:

Be it known that I, ELMER M. HICKS, a citizen of the United States, and a resident of Schenectady, in the county of Schenectady and State of New York, have invented a new and Improved Brake and Lock for Sliding Sashes, of which the following is a description.

My invention relates to means for holding 10 sliding window sashes when open to any desired extent and for locking the sashes in the closed position. The invention particularly relates to sash attachments involving the use of brake or stop elements adapted to 15 frictionally engage a guide rod on a window frame for holding the sashes in any given adjustment.

The general object of my invention is to provide a device of the character indicated, 20 adapted to be applied to upper and lower sashes respectively, and improved in various particulars whereby characteristic results are obtained among which are the following: The friction brake elements may be readily 25 adjusted to vary the pressure on the guide rod; locking elements are carried by the brake device to lock automatically with a relatively fixed element when a sash is in the closed position, and the various parts are so 30 formed and arranged as to promote convenience in their assemblage, as well as strength and durability.

Reference is to be had to the accompanying drawings forming a part of this specification.

Figure 1 is a front elevation of a window having my invention applied thereto;

Fig. 2 is a vertical section on the line 2—2, Fig. 1;

Fig. 3 is an enlarged side elevation of the devices relating particularly to the upper sash, a portion of the vertical guide rod common to the devices of both sashes being included;

Fig. 4 is an inverted plan view of the features shown in Fig. 3, the guide rod being in section;

Fig. 5 is a rear view of the carrying bracket shown in Figs. 3 and 4;

Fig. 6 is a side elevation of the lower sash attachment with a portion of the guide rod;

Fig. 7 is an inverted plan view of the features shown in Fig. 6, the guide rod being in section.

In the drawings the letter A indicates an upper sliding sash; B, a lower sliding sash,

and C, the window frame. The attachment for the upper sash includes a bracket 10 of general U-shape which preferably has cross braces 10^a therein between the top and bottom arms of the bracket and said bracket is of a size that when secured to the upper sash the front will lie beyond the lower sash B. The securing means for the bracket preferably consist of feet 11 thereon and having 60 screw holes 12, which feet, however, are not formed directly on the bracket 10 but on adjustable bars 13, lying against the outer faces of the upper and lower arms of the bracket and formed with slots 14 receiving 65 adjusting screws 15 which take at their ends into the arms of the bracket as indicated at 16, Fig. 3.

A friction stop or brake is provided, carried by the bracket 10 at the front and comprises a block or plate 17 rigid with said bracket and a relatively adjustable friction plate 18, between which elements 17, 18, is disposed a fixed guide rod 19 secured, as hereinafter described, at its upper and lower 80 ends to the window frame C. The block 18 is secured by a screw 20 extending therefrom and through the block 17, and preferably also, into the bracket 10 as indicated in Fig. 3, said screw being positioned at one side of 85 the guide rod 19. At the opposite side of the guide rod a thumb screw 21 passes through the plate 18 and secures the same to the block 17 and bracket 10. The screws, 20, 21, pass loosely through the plate 18 and 90 on the shank of the screw 21 is a tension spring 22 for varying the pressure of the elements 17, 18 on the guide rod 19.

The arrangement is such that the upper sash having applied thereto the bracket 10 carrying the brake blocks, will be held by the latter when the window is opened to any desired extent and the braking friction on the rod 19 may be varied by turning the screw 21 as will be obvious, the looseness of 100 the screw 20 permitting of the adjustment of varying the friction by the screw 21.

The upper end of the guide rod 19 is bent laterally to provide an arm 23, the end of which is secured as at 24 by a screw or the like to the frame B. A brace 25 is secured at its lower end of the arm 23 of the guide A and at its upper end to the top of the window frame C as at 25^a. The said arm 23 is adapted to be engaged by a latch 26 which 110 is pivotally secured by a screw 27 or the like to the block 17 or any equivalent relatively

fixed part movable with the bracket 10. The latch 26 includes an upstanding arm 28 terminating in a hook 29 and adapted to engage over the arm 23 when the upper sash 5 reaches the closed position. In connection with the latch I provide a stop plate 30 secured to the friction plate or block 18 on the outer face thereof, the screws 20, 21 serving for the purpose. Said stop plate 30 has 10 upper and lower stops 31, 32 between which the latch 26 may vibrate on its pivot 27 to a limited extent for engaging or disengaging the arm 23. In practice, when it is desired to unlock the sash A, the latch is rocked into 15 disengaged position by a finger of the operator while at the same time the sash is grasped to lower the same to any desired extent, the sash being held by the friction of the blocks 17, 18 in any given position. 20 Substantially the same elements as described are applied to the lower sash B, to frictionally engage the rod 19 and to lock the sash in the closed position. Thus, a bracket 10^b is of a width that when the bracket is 25 applied to the lower sash B, the parts carried thereby will be in position to coact with the rod 19 for holding or locking the sash. The bracket has securing feet 11^a integral thereof. 30 On the face of the bracket is a block 17^a and a friction block 18^a is provided, said elements 17^a, 18^a, corresponding with the elements 17, 18 and lying respectively at the back and front of the rod 19. Screws 20^a, 35 21^a and a spring 22^a are arranged in connection with the elements 17^a, 18^a and corresponding with the similar elements previously described. Also, a latch 26^a is pivotally secured to the block 17^a by a screw 27^a 40 and is inverted with respect to the latch 26^a,

the arm 28^a corresponding with arm 28, being pendent and terminating in a hook 29^a which is adapted to engage an arm 23^a at the lower end of the rod 19. A brace 25^b is secured at its upper end to the arm 23^a and 45 at its lower end as at 25^c, to the window frame. The arm 23^a is adapted to be engaged by the hook 29^a and in the manner described in connection with the latch 26.

I would state in conclusion that while the 50 illustrated example constitutes a practical embodiment of my invention, I do not limit myself strictly to the mechanical details herein illustrated, since manifestly the same can be considerably varied without departure from the spirit of the invention as defined in the appended claim.

Having thus described my invention, I claim as new, and desire to secure by Letters Patent:

An attachment for windows with sliding sashes, said sashes including a guide rod adapted to be secured to the window frame, a bracket adapted to be secured to a sash, a friction element rigid with the bracket, a second friction element, the guide rod being adapted to be received between said friction elements, a screw loosely securing the second friction element to the first friction element at a side thereof, a second screw serving to 70 secure the second mentioned friction element to the first friction element at the opposite side thereof from the first screw, whereby the guide rod may be accommodated between said screws, and a tension spring on the 75 shank of the second screw and subject to the action of the latter to vary the tension of the spring on the second friction element.

ELMER MARCUS HICKS.
